UNDERSHIRT

Florence G. Katz, Philadelphia, Pa.

Application June 10, 1954, Serial No. 30,910

Term of patent 3½ years

(Cl. D3—25)

FIG. 1

To all whom it may concern:

Be it known that I, Florence G. Katz, a citizen of the United States, residing at Philadelphia, State of Pennsylvania, have invented a new, original, and ornamental Design for Undershirt, of which the following is a specification, reference being had to the accompanying drawing.

Fig. 1 is a front view showing an undershirt according to the present invention, and illustrated partially folded to conserve space; and

Fig. 2 is a rear view showing the undershirt of Fig. 1.
I claim:

The ornamental design for an undershirt, as shown.
